Machine Company, Detroit, Mich., a corpora-
tion of Michigan

Application November 14, 1932, Serial No. 642,490

2 Claims. (Cl. 197—186)

This invention relates to a typewriter. It is particularly concerned with the general construction of a typewriter and comprehends a new manner of building and assembling a typewriter and enclosing it in an attractive casing.

Typewriter mechanisms are generally assembled in and supported by integral cast frames which are of an irregular box-like shape. The assembly of the mechanism in these frames is necessarily somewhat slow and awkward. Large openings have to be left in the sides of the casting to permit access to the typewriter mechanism and, when the typewriter is completed, the mechanism is almost entirely exposed at the sides, the front, and the rear. In fact, the cast frames comprise little more than corner posts connected by top and bottom braces. These corner posts and braces are finished on the outside to improve their appearance but the mechanism inside the cast frame is not nicely finished and viewed as a whole, the completed typewriter does not present a pleasing or finished appearance. So much of the mechanism is exposed that after a short period of use, the exposed mechanism becomes dirty, the dirt tends to interfere with proper operation and causes wear, and the machine looks like an assembly of dirty, unfinished levers, keys, gears, etc.

The present invention comprehends building a typewriter by starting on an entirely new and different basis. Instead of assembling the mechanism on a cast frame which forms the exterior surface of the machine, the mechanism is assembled in groups of parts and these groups are then mounted between two sheet-metal side plates which support the entire mechanism but which are not visible when the machine is completed. This facilitates the assembly of the machine and makes it unnecessary to use extreme care to avoid scratching the finish of a cast frame while the typewriter is being put together. After the machine is completely finished, an enclosing casing is detachably secured to the side plates. This casing is preferably made in a number of parts and mounted in such a way that each part may be independently removed to permit access to a given part of the machine without disturbing the remaining parts of the casing.

The general object of the invention is to provide an improved typewriter construction.

A more particular object is to provide a construction that will facilitate the assembly of a typewriter.

A further object is to provide an improved construction that will not only facilitate the as-

sembly but which will also improve the external appearance of the typewriter.

Other objects and advantages of the invention will appear from the following specification and drawings.

An embodiment of the invention is shown in the accompanying drawings in which:

Figure 1 is a perspective view of the complete typewriter;

Fig. 2 is a perspective view illustrating particularly the metal side plates that support the typewriter mechanism and to which the casing is attached;

Fig. 3 is a separated perspective of the metal panels making up the casing;

Fig. 4 is a perspective of one of the units of the typewriter mechanism which includes the type bar segment and the escapement mechanism; and

Fig. 5 is a perspective view of another unit of the typewriter mechanism including the ribbon feed and reverse.

The typewriter mechanism includes type bars controlled by depressible keys, a traveling paper carriage, and other usual parts making up a complete typewriter mechanism. It has not been considered necessary to illustrate all these parts in detail because an understanding of their details is not necessary for a comprehension of the present invention but some of them will be briefly referred to later. It is sufficient to know that the typewriter mechanism includes all the usual and necessary parts to make a complete machine.

The typewriter mechanism is supported by two side plates 10 and 11 (Fig. 2) which are stamped out of sheet metal. These two plates are alike and they are unfinished although they are given a treatment or coating to prevent rusting. The plates are provided with openings 12 and 13 to permit access to the typewriter mechanism for service and repair. Attached to each plate are two rubber covered feet 14 which are adapted to rest on a table or desk on which the typewriter may be placed. Since the two plates are alike, their manufacture is a very simple stamping and drilling operation.

The different groups of parts making up the typewriter mechanism are assembled separately as units and then attached to the side plates, the shafts or cross members on which the groups or units are assembled serving to space the side plates and form a bracing, a connecting and supporting structure between said plates.

One group of parts comprises the carriage unit 29 shown in Fig. 1. This group may be inde-

pendently assembled and it is then mounted upon the carriage rails 21 and 22 (Fig. 2). The rail 21 is connected to the side plates 10 and 11 and serves as a spacing and brace bar. The rail 22 is attached to a cross member 23 that extends between the side plates to space and brace them.

Another group of parts, shown in Fig. 4, includes the type bar segment 24 and the escapement mechanism 25. These parts are independently assembled as a unit on a sub-frame 26 having feet 27 by means of which the unit is attached to a cross member or plate 28 (Fig. 2) extending between the side plates 10 and 11, the attachment being by screws passing through the feet 27 and into threaded openings 29 in member 28.

Another group of parts, shown in Fig. 5, comprises the ribbon mechanism including the automatic ribbon reverse. This unit is provided with ribbon spool shafts 30 and 31 whose upper ends are adapted to support the ribbon spools. These ribbon spool shafts are driven by a drive shaft 32 and an automatic ribbon reverse is provided including a reverse lever 33. All these parts are assembled as a unit on a cross member 34 which is attached to the side plates 10 and 11 by screws through holes 35 and 36.

The key levers 37 (Fig. 1) and type actions 38 are mounted individually, the key levers being supported at their rear ends in a cross member 40 (Fig. 2) connected to the side plates 10 and 11 and being guided at their front ends by a comb plate 41 that extends between the side plates and forms a connecting and bracing member. The type actions 38 are, of course, pivoted on the type bar segment 24 after the unit containing it has been placed in position.

A shaft 43 (Fig. 2) extends between the side plates 10 and 11 and supports certain of the movable parts for case shifting, etc.

The front ends of the side plates 10 and 11 extend forwardly as shown in Fig. 2 and these front ends are joined by a cross member 42.

From the description thus far given, it will be observed that the typewriter mechanism is assembled in units and that these units are then assembled between two unfinished metal plates, certain portions of the units forming a spacing, bracing, connecting, and supporting structure for the plates so that when the units are assembled between the plates the whole structure is rigidly held together.

This unit assembly promotes efficient manufacture and the fact that the machine can be assembled between unfinished plates permits more rapid work as no attention need be paid to the finish on the side plates. In the completed machine these side plates do not form any part of the exterior, consequently, during the assembly of the machine, it is not necessary to use extreme care to prevent marring finished parts.

After the typewriter mechanism has been completely assembled between the side plates and is in workable condition, and after it has been tested, a nicely finished enclosing casing is detachably mounted on the side plates in order to enclose the typewriter mechanism on both sides, the front, and the rear. This gives the machine a very pleasing and finished appearance and, at the same time, encloses the mechanism to prevent dirt and moisture from readily getting into it.

This casing is preferably made in a number of separate parts comprising two side panels 50 and 51 (Fig. 3), a rear panel 52, and a front plate 53 or panel 54. A second front panel 54 is provided

which may or may not be considered a part of the casing.

The front plate 53 fits over the front cross bar 42 to which it is attached by means of screws 55 (Fig. 1) that are threaded into suitable bosses 56 (Fig. 2) on the bar 42. This front plate has side extensions 57 (Fig. 3) provided with openings 58 for a purpose that will presently appear.

The side panels 50 and 51 are alike, except that one is right and the other is left-handed. These side panels are shaped to fit over the respective side plates 10 and 11 and they are attached thereto by means of screws 60 and 61 (Fig. 1), the upper screw 60 being threaded into a boss 62 (Fig. 2) on the side plates, and the lower screw 61 being threaded into openings in a bar 63 that is attached to the side plates. It is to be understood that the exact manner of attaching these panels can be changed to suit the requirement.

The side panels 50 and 51 also have openings 64 (Fig. 3) for the receipt of screws 65 (Fig. 1) which are threaded into the openings 58 in the extensions 57 of the front panel 53 so that the side panels are united to the front panel when the side panels are placed in position.

The side panels 50 and 51 are bent laterally at their rear edges and provided with rear extensions 66 and 67 having threaded holes 68 for the receipt of screws 69 that hold the rear panel 30 in position.

The rear panel 52 is provided with openings 70 for loosely receiving the screws 69 which thread into the openings 68. The rear panel 52 is thus supported by the side panels 50 and 51 and the latter, in turn, are supported by the side plates 10 and 11.

The front face plate 54 is attached by means of screws 71 which thread into bosses 72 (Fig. 2) on the side plates 10 and 11.

From the above it will be seen that any one of the casing panels can be independently removed without removing any of the others. For example, the rear panel 52 may be taken off by taking out the screws 69, and all the remaining panels 45 are undisturbed. This permits access to the rear of the machine. Either of the side panels 50 or 51 may be removed by taking out the screws 69 at the rear on the selected side and then removing the screws 60, 61 and 65. This permits access 50 to the selected side of the machine and does not disturb the other casing panels. The front panel 53 may be removed by taking out the screws 55 and 65 without disturbing the remaining parts of the casing. Likewise the front plate 54 may be 55 independently removed by taking out the screws 71.

Easy access may thus be had to any selected part of the typewriter mechanism and, at the same time, the typewriter presents a finished and attractive appearance. The typewriter mechanism is not exposed in the manner that has heretofore been customary.

It is to be understood that the structure shown is for purposes of illustration only and that variations may be made therein without departing from the spirit and scope of the invention as defined by the appended claims.

By the use of the term "a pair of independent unfinished sheet metal side plates", as employed 70 in my claims, I intend to define and be restricted to spaced sheet metal plates of the character generally shown by reference numerals 10 and 11 which are used for securing the assemblages of the typewriter mechanism and which are not 75

finished or enameled or configured in such a way as to constitute the exterior frame of the typewriter.

What is claimed is:

- 5 1. A standard-size, front-strike typewriter comprising a pair of spaced, flat, interchangeable, and unfinished sheet-metal side plates provided with openings for the receipt of members that are to be attached to them and with openings to permit access to mechanism that may be located 5 between them, typewriter mechanism, including cross members and pre-assembled groups of parts, positioned between and attached to said plates to form a connecting and bracing structure making, in combination with said side plates, a rigid assembly comprising a complete and operative typewriter that may be quickly and easily assembled, without the use of special care to avoid damage to the finish of the parts, by pre-assembling groups of parts and then assembling and connecting them together with said cross members between said unfinished plates, and a finished casing detachably secured to said side plates, said casing being attached to said completed assembly and acting to cover said side plates and to completely enclose said typewriter mechanism while leaving exposed such parts as must remain exposed for operation, said casing having independent side and rear panels detachably secured to said unfinished sheet metal side plates and to each other whereby any one of said 20 panels may be independently removed without disturbing the operative position of the remaining panels to give access to a given part of the machine.
- 25 2. A standard-size, front-strike typewriter com-

prising a pair of spaced, flat, interchangeable, and unfinished sheet-metal side plates provided with openings for the receipt of members that are to be attached to them and with openings to permit access to mechanism that may be located 5 between them, typewriter mechanism, including cross members and pre-assembled groups of parts, positioned between and attached to said plates to form a connecting and bracing structure making, in combination with said side plates, a rigid assembly comprising a complete and operative typewriter that may be quickly and easily assembled, without the use of special care to avoid damage to the finish of the parts, by pre-assembling groups of parts and then assembling and connecting them together with said cross members between said unfinished plates, and a finished casing detachably secured to said side plates, said casing being attached to said completed assembly and acting to cover said side plates and to completely enclose said typewriter mechanism while leaving exposed such parts as must remain exposed for operation, said casing having independent side and rear finished panels, the side panels being detachably secured to the said unfinished sheet metal side plates and the rear panels being detachably secured to the side panels, whereby any one of said panels may be independently removed without disturbing the operative position of the remaining panels for access to 20 a given part of the machine.

JOSEPH A. SUMMERLEE.
